(57) **CLAIM**

The ornamental design for a dual ring jewelry setting, as shown and described.

DESCRIPTION

FIG. 1 is a top front perspective view of a dual ring jewelry setting;

FIG. 2 is a front elevation view thereof, with the rear elevation view being a mirror image thereof;

FIG. 3 is a right side view thereof, with the left side view being a mirror image thereof;

FIG. 4 is a top elevation view thereof; and,

FIG. 5 is a bottom elevation view thereof.

The broken lines shown in the drawings represent environmental subject matter only and form no part of the claimed design.
